UNITED STATES PATENT OFFICE.

HARVEY HUBBELL, OF BRIDGEPORT, CONNECTICUT

CHAIN-GUIDE FOR PULL-SOCKETS.

No. 817,485.

Specification of Letters Patent.

Patented April 10, 1906.

Application filed July 14, 1905. Serial No. 269,635.

To all whom it may concern:

Be it known that I, HARVEY HUBBELL, a citizen of the United States, residing at Bridgeport, county of Fairfield, State of Connecticut, have invented a new and useful Chain-Guide for Pull-Sockets, of which the following is a specification.

This invention has for its object to provide a chain-guide for pull-sockets which shall be so constructed that it may be attached centrally and radially to the socket instead of at one side and tangential thereto, thus greatly improving the contour and general appearance of the socket, and which shall provide for the rise and fall of the segment in use, giving at all times a smooth and rounded runway for the chain. This result I accomplish by making the guide bell-shaped at its inner end and providing a shoulder which rests against the outer side of the shell of the socket and a hub which passes through the shell and whose edge is then turned outward and closed down upon the inner side of the shell.

25 A further object of the invention is to provide a two-part chain-guide the top or outer part of which shall be made in varying lengths to adapt it to pass through a "husk," so-called, or other ornamental fixture used in connection with an incandescent lamp and engage a base attached to the socket.

With these and other objects in view the invention consists in the special construction of chain-guides which I will now describe and then specifically point out in the claims hereunto appended.

In the accompanying drawings, forming a part of this specification, in which reference characters are used to indicate the several parts, Figure 1 is an elevation of an incandescent lamp and a husk, illustrating the use in connection therewith of my novel chain-guide; Fig. 2, a horizontal section on the line 2-2 in Fig. 1 looking up; Fig. 3, a similar section illustrating a form of my novel chain-guide made in a single piece, and Fig. 4 is an enlarged sectional view of a two-part guide detached.

10 denotes an incandescent lamp; 11, the 50 socket; 12, the segment; 13, the chain; 14, a husk, and A my novel chain-guide as a whole. As the construction of the socket mechanism has nothing to do with my present invention, it will not be described in detail. It is sufficient for the purposes of this specification to say that the chain passes through the guide

and the inner end of the chain passes around the periphery of the segment and is attached thereto at the end opposite to the inner end of the guide. It is of course well understood that in use the segment has more or less of a rising-and-falling movement—that is, a movement bodily in the direction of the length of the shell—in addition to its oscillatory movement. Heretofore, in order that the pull 60 upon the chain might be as direct as possible, it has been customary to place the guide at one side of the shell and substantially tangential thereto. This construction is objectionable for several reasons—notably, that the general configuration of the shell is marred thereby, that it is more expensive to manufacture, and that it is not convenient to use the guide in connection with a husk or other ornamental fixture surrounding and concealing the socket. These objections I 70 wholly overcome and am enabled to attach the guide centrally to the socket and radially thereto and make the chain run freely therein by making the inner end of the guide bell-shaped, as at 15. This enables me to carry the chain around farther on the segment, which is a great improvement in practice and provides a smooth rounded runway for the chain in any position of the segment, all 80 angles for the chain to pass over being avoided and a smooth rounded surface being provided, over which the chain will pass freely.

In Figs. 1, 2, and 4 I have illustrated a form of the invention in which the guide is made in two parts in order that it may be used in connection with a husk or other ornamental fixture. In this form 16 denotes the base of the guide, which is provided with a shoulder 17, adapted to bear against the outer side of the shell, and a hub 18, which passes through a hole in the shell and is opened outward and closed down upon the inner side of the shell, as clearly shown in Figs. 2 and 3. The outer end of the base is provided with an internal screw-thread terminating in a shoulder 19. 20 denotes the top or outer part of the guide, which is preferably bell-shaped at its outer end, as at 21. At the inner end of the top is an external screw-thread terminating in a shoulder 22. This thread is adapted to engage the internal thread in the base, the end of the top engaging the shoulder in the base and the shoulder on the top engaging the outer end of the base, so as to leave the guide as a whole as perfectly finished both internally and externally.

as if made in a single piece. The tops are made of different lengths to adapt them for use with husks and various other ornamental fixtures. When used in connection with a 5 husk, the inner end of the top is passed through a hole in one of the leaves of the husk and engages the base which lies within the husk. By detaching the top the socket may be removed from the husk and a new one 10 placed therein, the husk not being disturbed in changing lamps or sockets.

In the form illustrated in Fig. 3 the entire 15 guide is made in a single piece, both the inner and outer ends being made bell-shaped, as before, and the inner end being provided with a shoulder and attaching-hub, by which the guide as a whole is attached in place in the same manner as the hub is attached in the other form.

20 Having thus described my invention, I claim—

1. A chain-guide for pull-sockets compris-

ing a base having a shoulder adapted to engage the outer side of a socket-shell, a hub adapted to be passed through a socket-shell 25 and closed down upon the inner side thereof and a screw-thread at its outer end and a top having a corresponding screw-thread by which it may be attached to the base after the latter is attached to a socket-shell. 30

2. The combination with a pull-socket shell and a husk, of a chain-guide comprising a base having a shoulder adapted to engage the outer side of the socket-shell and a hub adapted to be passed through the shell and 35 closed down upon the inner side thereof and a top adapted to be passed through the husk and engage the base.

In testimony whereof I affix my signature in presence of two witnesses.

HARVEY HUBBELL.
